MAGNETIC SEPARATOR

Robert J. Linney, Port Henry, N. Y.

Application November 14, 1942, Serial No. 465,550

13 Claims. (Cl. 209—225)

This invention relates to material separating apparatus and more particularly to an improved form of magnetic separator for concentrating iron ore or other magnetic materials.

Iron ore, as mined, commonly contains substantial quantities of impurities and waste matter. To separate such materials magnetic separators have been devised and used in which an endless belt is moved through a magnetic field and a mixture of ore and impurities discharged against the belt which passes through a tank of water whereby certain waste matter and impurities are removed.

The present invention relates to improvements in magnetic separators of the belt type, and it is among the objects of my invention to provide a magnetic separator which will give an increased output as compared to prior devices and which will deliver a high grade of concentrates with an extremely low iron loss in the tailings.

Other objects of my invention include: the provision of means for causing all of the cleaning water to flow in one direction counter to the movement of the magnetic material; the provision of a separator in which the belt is never submerged and which therefore eliminates the necessity of providing a water-tight box for enclosing the electro-magnets which create the magnetic field; the provision of a separator in which the material being handled is subjected to a series of separate washings with clean water; and the provision of a magnetic separator in which the delivered concentrates are substantially free from soluble impurities.

The above and other objects of my invention will appear from the following description of one embodiment thereof, reference being had to the accompanying drawings in which:

Figure 1 is a somewhat diagrammatic vertical, longitudinal, sectional view through a magnetic separator embodying my invention.

Figure 2 is a fragmentary enlarged view, generally similar to Figure 1, but showing only the feed inlet and parts adjacent thereto.

Figure 3 is a transverse cross-sectional view taken substantially on line 3—3 of Figure 1.

Figure 4 is a transverse cross-sectional view taken approximately on line 4—4 of Figure 1.

Figure 5 is a side-elevational view of a magnetic separator embodying the present invention and including structural features additional to those shown in Figs. 1 to 4;

Figure 6 is an enlarged fragmentary end-elevational view of a part of the feeding mechanism of Fig. 5;

Figure 7 is a cross-sectional view taken on line 7—7 of Fig. 6;

Figure 8 is a fragmentary sectional view taken on line 8—8 of Fig. 7; and,

Figure 9 is an enlarged view showing the relative positions of the magnets and the transverse spray pipes of Fig. 1.

In certain previous wet magnetic separators with which I am familiar the belt is submerged in a bath of water. With this type of equipment the level of water in the bath must be maintained at the proper point at all times. This requires constant attention. Further, in the submerged type of wet separator, substantial quantities of the floating waste and soluble materials, such as phosphorous colloid, are carried over into the concentrate. With my apparatus, however, any such material is instantly washed away by clean water, and the concentrates are delivered substantially entirely free from such impurities.

As is best seen in Figure 1, my improved separator includes an endless belt 1, supported on suitable sheaves or pulleys 2 and 3. Mounted on the shaft 4 of the pulley 3 is a drive pulley 5 engaged by the driving belt 6 which may extend any suitable source of power (not shown). By this means the pulley 3 is driven in the direction of the arrow (Figure 1). The lower belt supporting pulley 1 is mounted on the frame structure 7 which also supports the tailings hopper 8. Supporting members 9, 10 and 11 carry the generally inclined collecting apparatus which includes concentrator hopper 12 and spaced hoppers 13 and 14 for tails or middlings. The shaft 4 and pulleys 3 and 5 are mounted on the upper part of the supporting structure. Trough forming side walls 15 and 16 (Figure 3) are disposed on either side of the lower reach of the belt 1 and are connected to the launder plates 28, 29 and 30 as later described.

Transverse beams 17 extend across between the upper portion of the supporting framework for the separator and carry a housing structure 18 on the bottom of which are mounted a plurality of electro-magnets 19. Spaced belt engaging bars 20, preferably made of wood, are secured to the bottom of the magnet housing 18 and are arranged to engage the lower reach of the belt 1. A group of the magnets 19, disposed at the lower part of the concentrator, is connected to the supply line 21 through a switch 22 and a variable resistance or other suitable control means 23 is preferably provided to regulate the magnetic force of this group of magnets. In like manner the upper group of magnets is

connected through conductors 24 and switch 25 to a supply line 26 and a variable resistance 27 is employed to modify the magnetic effect as desired.

Below the bottom surface of the belt 1 is a trough consisting of a series of inclined launder plates 28, 29 and 30 composed of non-magnetic material. These plates are spaced closely adjacent to the bottom side of the belt 1 and are preferably mounted for adjustment toward and away from the belt in any suitable manner (not shown). The lower end of the top launder plate 28 is bent slightly downwardly at 28' to provide an outlet 28'' for water and non-magnetic materials. In like manner the lower end of the center launder plate 29 is curved downwardly at 29' providing an outlet 29'' between it and the upper end of the bottom launder plate 30. The launder plates are connected at their side edges to the lower edges of the inclined trough side members 15 and 16.

The discharge from the lower end of the launder plate 30 is into the tailings hopper 8 which is provided with an outlet pipe 31 for removing the tailings to a suitable place of disposal. In like manner the opening 28'' discharges into the hopper 13 having an outlet pipe 32 and the opening 29'' discharges into the hopper 14 which has an outlet pipe 33.

Material to be treated, consisting of a mixture of magnetic and non-magnetic materials and water, is fed through a supply pipe 34 into the feed hopper 35. As seen in Figure 3 this feed hopper 35 extends across the full width of the belt 1 and feeds the material up against the under-side of the belt. A transversely extending pipe 36 lies in the hopper 35 and is provided with a plurality of discharge holes 37. Water under pressure is fed into the pipe 36 and discharged through the outlets 37 against the under-side of the belt as seen in Figure 3.

The magnetic field from the magnets 19 causes any magnetic material in the mixture to be drawn up against the under-side of the belt which moves upwardly from left to right in Figure 1 and carries with it the magnetic material.

Clean water fed through the pipe 36 flushes a substantial part of the non-magnetic waste materials down over the launder plate 30 into the tailings hopper 8 and the belt, due to its upward movement, carries the magnetic material, together with foreign material which has not been eliminated, upwardly over the next launder plate 29. Spray pipes 38 and 39, similar to the pipe 36 and similarly provided with a series of spray outlets, are mounted in the launder plate 29 with their outlets substantially flush with the top surface of the plate and direct sprays of water upwardly against the belt 1. Gravity causes this water to flow downwardly counter to the upward movement of the belt and during this downward movement the clean water from the sprays 37 and 38 washes additional non-magnetic material from the belt. This material is discharged through the opening 29'' into the hopper 14, and some may also pass on down over the launder plate 30 into the hopper 8. It will be understood that, if any magnetic material is washed from the belt it will be again picked up against the belt by the action of the magnetic field before it can drop into the tailings hopper.

The launder plate 28 is also supplied with spray pipes 39 and 40 and these function in the same manner as those previously described. The material discharge through the slot opening 28''

5 into the hopper 13 will be either tailings or middlings, depending upon the size of material being treated by the separator. The water from the spray jets 39 and 40 flows downwardly by gravity in a direction opposite to the movement of the belt 1 and the magnetic material which is adhered to the belt. As the belt moves upwardly beyond the upper magnet 19 the magnetic influence on the material ceases and the magnetic concentrates drop into the hopper 12 which is provided with an outlet pipe 41. A spray pipe 42, extending across the width of the belt and provided with a plurality of spray nozzles in a manner similar to pipes 36, 37, etc., is disposed adjacent the pulley 3 and washes any adhering concentrate material from the belt.

20 By inclining the belt 1 throughout its entire length, disposing a series of launder plates adjacent the bottom inclined surface of the belt, and directing a series of spaced clean water sprays against the material on the belt a plurality of separate cleaning operations are effected upon the material which is fed through the supply pipe 34. All possibility of contaminated water being discharged with the concentrates is eliminated due to the fact that the flow of washing water is all downwardly counter to the movement of the belt and material being handled. It will be understood that all parts of the hoppers, sprays, pipes, etc., which come within the magnetic field of the magnets 19 are preferably made of non-magnetic material such as brass or bronze. The major part of the water which is used in separating the material is discharged into the tailings and this results in a high quality concentrate output. As any magnetic particles which may be washed off from the belt, after having once been adhered thereto, will flow downwardly with the water in the space between the launder plates and the belt in close proximity to the belt a large percentage of such particles will again be picked up by the belt and the iron loss in the tailings is thus reduced to a very low value.

45 By using my combination of pressure jets and gravity action a very prompt removal of non-magnetic material is obtained and thus the capacity of the unit is increased over that of other types of wet separators of comparable size. In 50 operation the strength of the magnetic field at the lower and upper portions of the belt will be regulated to give the most efficient separating results and the speed of the belt will be correlated with the feed through the supply pipe 34 and the water discharge through the cleaning jets.

The apparatus of Fig. 5 is quite similar to the apparatus of Figs. 1 to 4. The belt 1 passes around idler pulley 2 and drive pulley 3, the latter being driven by motor 3a and belt 3b. The lower reach of the belt 1 moves upwardly, as is indicated by the arrow just below pulley 3. A tailings hopper 7 is located below the lower end of the belt, a concentrates hopper 12 is located near the upper end of the belt, and middlings hoppers 13 and 14 may be disposed between hoppers 7 and 12 and below passages 29a thru which material may be discharged from the trough. If desired, these hoppers 13 and 14 may discharge into a catch pan 15a or the hoppers may be omitted or the two hoppers combined into one large hopper.

70 When a two-part separation is desired, namely, concentrates and combined tailings and middlings, the material passing thru the openings

29a may be collected in hopper 1. When a three-part separation is desired, the middlings passing thru openings 29a are collected in hoppers 13 and 14 or a hopper substituted for those hoppers.

Beneath the lower reach of the belt is disposed a trough A composed of non-magnetic material and similar to that shown in Figs. 1, 2 and 3, the trough having one or more openings 29a in its bottom wall for the escape of liquid and solids therethru. The trough A has side flanges 29b which are secured to flanges 29c on the machine frame by adjusting connections 29d. By adjusting connections 29d the bottom of trough A may be moved toward and away from the belt and magnets and thus kept within the magnetic field of the magnets. A housing 18, similar to that shown in Figs. 1 to 3 is disposed closely adjacent to the upper surface of the lower reach of the belt 1 and encloses a plurality of magnets 19a so that liquid in the trough may not have free access to the magnets.

Pipes 34a serve to convey a mixture of water and material to be separated to opposite ends of feed box 35a which is disposed under the lower reach of the belt 1 and some little distance from the lower or tailings discharge end of the trough A. This feed box, as is better shown in Figs. 7 and 8, is generally rectangular in cross-section and is open at the top for its full width and for a length which is somewhat less than the width of the belt 1. Within the feed box 35a are disposed two opposed feed-distributing nozzles 40 and a feed diluting pipe 41 having outlets in its upper surface.

It will be understood that when a mixture of water and ore, consisting of magnetic and non-magnetic materials, is delivered thru pipes 34a into opposite ends of the feed box 35a, the mixture will fill the feed box and flow thru the open upper end thereof into the trough A where the water will be free to flow downwardly in the trough, carrying with it non-magnetic materials, and the magnetic particles may be attracted to and carried upwardly in the trough by the belt. In order that the mixture in the feed box may be distributed properly into the trough, valves (not shown) are employed to regulate the flow of water thru nozzles 40. When the flow of liquid thru the opposed nozzles 40 is equal, the solids will be prevented from settling to the bottom of the box and also the mixture will feed up into the trough and into contact with the belt more or less equally thruout the full length of the top opening of the feed box. When more liquid is admitted thru one nozzle 40 than thru the other, settling out of solids will be prevented and also a greater amount of mixture may be fed against one part of the belt than against another part. In this manner the mixture will be kept quite uniform and the amount of mixture that is fed from the feed box against different parts of the belt may be regulated as desired.

The liquid discharged thru pipe 41 serves to agitate and dilute the mixture of water and solids and to promote the feeding of the mixture thru the top opening of the feed box.

It will be noted, from consideration of Fig. 5, that the feed box 35a is disposed some distance from the lower end of the trough A. This location has been found to be desirable because magnetic particles which may not be immediately brought into contact with the belt can move some distance along the trough and then be picked up by the belt before the particles can escape from the lower end of the trough. This relative

location of the feed box has been found to be responsible, at least in part, for a considerable reduction in the percentage of magnetic particles which previously were collected in the tailings hopper.

In Fig. 9 is shown a modification of the spray apparatus of Figs. 1 to 3. The header pipe 42 which extends along one side of trough A opens into pipes 43 which extend from header pipe 42 across the trough A and have openings in their top surface to discharge water upwardly in the trough against the lower surface of the belt. These pipes 43 correspond to pipes 37, 38, 39 and 40 of Fig. 1, but are purposely positioned beneath the centers of superimposed magnets 19a. In other words, water discharged from pipes 43 will impinge against the belt in line with the central portions of the ends of the super-imposed magnets.

One purpose of this location of these parts is to release non-magnetic material which may have been entrapped by magnetic material and thereby carried along by the belts. Since the transverse rows of magnets are alternately of opposite polarity, the weakest points in the magnetic fields are on transverse lines passing thru the centers of the ends of the transverse rows of magnets. When water is sprayed toward these points of lowest magnetic force, it tends to disturb solid particles held against the belt by the magnets. When a plurality of pieces of magnetic material are attracted to the belt by a part of the strong magnetic field, those pieces may carry with them non-magnetic pieces. When water is sprayed against that collection of magnetic and non-magnetic pieces in the weaker parts of the magnetic field, the pieces of material may be shifted about on the belt or may even be dislodged therefrom. In this manner the non-magnetic pieces are permitted to escape from a position where they were entrapped by the magnetic particles and may thus be washed down along the trough by the stream of water flowing therein while the magnetic pieces are again attracted to and carried along by the belt. As a result of positioning the spray pipes 43 as has just been described, the amount of non-magnetic material which is carried into the concentrates hopper is considerably reduced.

Another advantage of the present invention is that the amount of phosphorous which is carried into the concentrates hopper is considerably reduced over prior practice. This advantage is traceable to the fact that substantially all the water discharged into the trough escapes into the tailings or middlings hoppers and very little of it is discharged into the concentrates hopper and such of that water as does reach the concentrates hopper is clear and clean because of the repeated washings to which the ore has been subjected in the lower parts of the trough; and to the further fact that there is very little dirt or soluble material left on the belt when it reaches the topmost pipe 43.

This application is a continuation-in-part of my copending application Ser. No. 365,659, filed on or about November 14, 1940.

Although I have described the illustrated embodiment of my invention in considerable detail, it will be understood by those skilled in the art that the drawings are somewhat schematic and that numerous variations and modifications can be made without departing from the spirit of my invention. I do not, therefore, wish to be limited to the particular apparatus shown and described

but claim as my invention all forms thereof coming within the scope of the appended claims.

What is claimed is:

1. A magnetic separator comprising an inclined trough having a bottom provided with an opening therethru between the ends thereof, a hopper disposed below said trough to receive material passing through the opening, an endless belt having an inclined lower reach movable upwardly adjacent to the bottom of said trough, electromagnets disposed along and adjacent to the top surface of said reach of said belt, means to discharge liquid against the lower surface of said reach of the belt at elevations above said opening, and means to deliver materials into the trough near the lower end thereof.

2. In a wet magnetic separator, an endless belt, spaced pulleys having horizontal axes for supporting said belt with at least a portion of its lower reach inclined upwardly, and for driving said belt whereby said inclined portion moves upwardly, a plurality of launder plates below said inclined portion of said belt and spaced therefrom, a plurality of outlet openings between said plates and spaced along the length of said belt, a plurality of spaced water supply means for discharging water into the space between said plate and belt and against the lower surface of said belt, electro-magnetic means above said inclined portion of said belt for attracting magnetic material to said belt, means disposed between the ends of the lowermost launder plate for discharging material to be separated into the space between said plate and belt, hoppers below said plates positioned to receive and segregate the discharge from said spaced discharge openings, and a concentrates hopper below the upper end of the uppermost plate and extending beyond the upper end of said electro-magnetic means.

3. A magnetic separator comprising an inclined trough having a bottom provided with openings therethru at different elevations, hoppers disposed below said trough to receive material passing therethrough, an endless belt having an inclined lower reach movable upwardly adjacent to the bottom of said trough, electromagnets disposed along and adjacent to the top surface of said reach of said belt, means to discharge liquid against the lower surface of said reach of the belt at elevations above said openings, and means to deliver materials into the trough near the lower end thereof.

4. A magnetic separator comprising an inclined trough having a bottom provided with openings therethru at different elevations, hoppers beneath said openings to receive material discharged therethru, other hoppers beneath the upper and lower ends of said bottom to receive material passing thereover, an endless belt having an inclined lower reach movable upwardly in and adjacent to the bottom of said trough, electromagnets disposed along and adjacent to the top surface of said reach of said belt, means to discharge liquid against the lower surface of said reach of the belt at elevations above said openings, and means to deliver materials into the trough near the lower end thereof.

5. A magnetic separator comprising an inclined trough having a bottom provided with openings therethru at different elevations, hoppers beneath said openings to receive material discharged therethru, other hoppers beneath the upper and lower ends of said bottom to receive material passing thereover, an endless belt having an inclined reach movable upwardly in and adjacent

to the bottom of said trough, electromagnets disposed along and adjacent to the top surface of said reach of said belt, means to discharge liquid thru said trough bottom against the lower surface of said reach of the belt at elevations above each of said openings, and means to deliver materials into the trough thru the lower part of said bottom.

6. A magnetic separator comprising an inclined trough having a bottom formed by a plurality of plates spaced apart to provide openings therebetween at different elevations, hoppers beneath said openings to receive material discharged therethru, other hoppers beneath the upper and lower ends of said bottom to receive material passing thereover, an endless belt having an inclined lower reach movable upwardly in and adjacent to the bottom of said trough, electromagnets disposed along and adjacent to the top surface of said reach of said belt, means to discharge liquid against the lower surface of said reach of the belt near the upper end of each plate, and means to deliver materials to be separated into the trough near the lower end thereof.

7. A magnetic separator comprising an endless belt having an inclined lower reach, means to drive said reach of the belt upwardly, a plurality of electromagnets adjacent to the upper surface of said reach of the belt, a plurality of inclined launder plates disposed adjacent and substantially parallel to the lower surface of said reach, said plates being spaced apart from each other to provide openings at their lower ends for the discharge of materials therethru, hoppers beneath said openings to receive materials discharged therethru, a hopper beneath the lower end of the lowermost plate to receive material discharged over said end of said plate, a hopper below the upper end of the uppermost plate to receive material carried beyond said end of said plate by said electromagnets and then released by the latter, means for delivering material to be separated thru the lowermost plate, and means for delivering liquid into the space between each of said plates and the opposed surface of said belt.

8. A magnetic separator comprising an endless belt having an inclined lower reach movable upwardly, a plurality of electromagnets disposed along and adjacent to the top surface of said reach of said belt, an inclined, open-ended, non-magnetic trough disposed below said reach of the belt and in the magnetic field of said magnets, said trough bottom having an opening therethru between its ends, means for feeding an aqueous mixture of magnetic and non-magnetic materials to be separated into said trough near its lower end, and means for discharging liquid into said trough and against the belt at elevations above said opening and opposite the centers of said magnets.

9. A magnetic separator comprising an endless belt having an inclined lower reach movable upwardly, a plurality of electromagnets disposed along and adjacent to the top surface of said reach of said belt, an inclined, open-ended, non-magnetic trough disposed below said reach of the belt and in the magnetic field of said magnets, said trough bottom having an opening therethru between its ends, means for feeding an aqueous mixture of magnetic and non-magnetic materials to be separated into said trough near its lower end, said feeding means including a feed box positioned below, extending across, and opening at its top into said trough, said box having openings at its opposite ends for entry thereinto

of said aqueous mixture, and means in said box for controlling the distribution of said mixture into said trough, and means for discharging liquid into said trough and against the belt and at elevations above said opening.

10. A magnetic separator comprising an endless belt having an inclined lower reach movable upwardly, a plurality of electromagnets disposed along and adjacent to the top surface of said reach of said belt, an inclined, open-ended, non-magnetic trough disposed below said reach of the belt and in the magnetic field of said magnets, said trough bottom having an opening therethru between its ends, means for feeding an aqueous mixture of magnetic and non-magnetic materials to be separated into said trough near its lower end, said feeding means including a feed box positioned below, extending across, and opening at its top into said trough, said box having openings at its opposite ends for entry thereinto of said aqueous mixture, and means in said box for controlling the distribution of said mixture into said trough, and means for discharging liquid into said trough and against the belt and at elevations above said opening and opposite the centers of said magnets.

11. In a magnetic separator having a movable member for propelling magnetic particles, a plurality of magnets on one side of said member, and confining means on the other side of said member within the magnetic field of said magnets, said member and confining means defining a space for an aqueous mixture of magnetic and non-magnetic particles to be separated, means for feeding an aqueous mixture of magnetic and non-magnetic materials into said space, said feeding means comprising a feed box positioned below said member and opening at the top into said space across a major part of the width of said member, conduits opening into opposite ends of said box for delivering an aqueous mixture of metallic and non-metallic particles into the box, and means near each end of said box and adjacent to its bottom for discharging liquid under pressure lengthwise of the box to control the distribution of solid particles in the aqueous mixture passing thru the top of said feed box.

12. In a magnetic separator having a movable member for propelling magnetic particles, a plu-

rality of magnets on one side of said member and confining means on the other side of said member within the magnetic field of said magnets, said member and confining means defining a space for an aqueous mixture of magnetic and non-magnetic particles to be separated, means for feeding an aqueous mixture of magnetic and non-magnetic materials into said space, said feeding means comprising a feed box positioned below said member and opening at the top into said space across a major part of the width of said member, conduits opening into opposite ends of said box for delivering an aqueous mixture of metallic and non-metallic particles into the box, and means extending lengthwise of the box near its bottom for discharging liquid under pressure upwardly in a plurality of streams to agitate and dilute the aqueous mixture and to promote the feeding of the mixture thru the top of said feed box.

13. In a magnetic separator having a movable member for propelling magnetic particles, a plurality of magnets on one side of said member and confining means on the other side of said member within the magnetic field of said magnets, said member and confining means defining a space for an aqueous mixture of magnetic and non-magnetic particles to be separated, means for feeding an aqueous mixture of magnetic and non-magnetic materials into said space, said feeding means comprising a feed box positioned below and extending across said member and opening at its top into said space across a major part of the width of said member, conduits opening into opposite ends of said box for delivering an aqueous mixture of metallic and non-metallic particles into the box, means near each end of said box and adjacent to its bottom for discharging liquid under pressure lengthwise of the box to control the distribution of solid particles in the aqueous mixture passing thru the top of said feed box, and means extending lengthwise of said box near its bottom to discharge upwardly a plurality of streams of liquid under pressure to agitate and dilute the aqueous mixture and to promote the feeding of the mixture thru the top of said feed box.

ROBERT J. LINNEY.
